(57) **CLAIM**

The ornamental design for a remote control vehicle chassis adapter assembly, as shown and described.

DESCRIPTION

FIG. 1 is an isometric view of a first embodiment of a remote control vehicle chassis adapter assembly.

FIG. 2 is a top view of the remote control vehicle chassis adapter assembly of FIG. 1.

FIG. 3 is a bottom view of the remote control vehicle chassis adapter assembly of FIG. 1.

FIG. 4 is a front view of the remote control vehicle chassis adapter assembly of FIG. 1.

FIG. 5 is a rear view of the remote control vehicle chassis adapter assembly of FIG. 1.

FIG. 6 is a left view of the remote control vehicle chassis adapter assembly of FIG. 1.

FIG. 7 is a right view of the remote control vehicle chassis adapter assembly of FIG. 1.

FIG. 8 is an isometric view of a second embodiment of a remote control vehicle chassis adapter assembly.

FIG. 9 is a top view of the remote control vehicle chassis adapter assembly of FIG. 8.

FIG. 10 is a bottom view of the remote control vehicle chassis adapter assembly of FIG. 8.

FIG. 11 is a front view of the remote control vehicle chassis adapter assembly of FIG. 8.

FIG. 12 is a rear view of the remote control vehicle chassis adapter assembly of FIG. 8.

FIG. 13 is a left view of the remote control vehicle chassis adapter assembly of FIG. 8.

FIG. 14 is a right view of the remote control vehicle chassis adapter assembly of FIG. 8.

FIG. 15 is an isometric view of a third embodiment of a remote control vehicle chassis adapter assembly.

FIG. 16 is a top view of the remote control vehicle chassis adapter assembly of FIG. 15.

FIG. 17 is a bottom view of the remote control vehicle chassis adapter assembly of FIG. 15.

(Continued)

FIG. 18 is a front view of the remote control vehicle chassis adapter assembly of FIG. 15.

FIG. 19 is a rear view of the remote control vehicle chassis adapter assembly of FIG. 15.

FIG. 20 is a left view of the remote control vehicle chassis adapter assembly of FIG. 15; and,

FIG. 21 is a right view of the remote control vehicle chassis adapter assembly of FIG. 15.

The broken lines and the areas within them in FIGS. 15, 16, 17, 19, 20, and 21 depict portions of the remote control vehicle chassis adapter assembly that form no part of the claimed design.
